BALL-POINT FOUNTAIN PENS

David J. Esterow, New York, N.Y.

Application June 20, 1956, Serial No. 592,569

4 Claims. (Cl. 120—42.03)

This invention relates to writing pens and more particularly to those of the ball-point construction.

It is an object of the present invention to provide means by which the ink cartridge bearing the ball-point is advanced and retracted and guided in such movement in a manner to insure easy axial sliding movement of the cartridge within the pen barrel.

It is an object of the invention to provide locking means for maintaining the cartridge at its advanced or forward position which locking means shall include a guiding slot and an element guided therein and constantly disposed in said slot while the cartridge is advanced, retracted or in any intermediate position.

It is an object of the invention to provide, as a part of the cartridge-advancing means, a yoke-shaped spring element, actuated in one direction by a manually-operated plunger, which yoke-shaped element shall be provided with a pair of divergent springy arms, at least one of which shall be apertured adjacent to the point of fold of the yoke-shaped element, to thereby increase the springiness and resilience of the yoke and enable it to be used in pen barrels of various diameters.

It is an object of the invention to provide guiding means for the yoke which shall prevent inadvertent displacement of the yoke relative to its guide slot and which shall have other advantages apparent to those skilled in this art.

In the accompanying drawing, wherein an illustrative embodiment of the invention is disclosed, Fig. 1 is a face view of the blank from which the spring yoke, forming part of the improved propelling means, is made;

Fig. 2 is a side view of the yoke;

Fig. 3 is a front elevational view of the yoke;

Fig. 4 is a longitudinal sectional view through the body or barrel of a pen, showing the cartridge-advancing and retracting mechanism therein;

Fig. 5 is a face view of a portion of the barrel, showing the slot formed therein;

Fig. 6 is a sectional view, taken substantially on the line 6—6 of Fig. 2, looking in the direction of the arrows; and

Fig. 7 is a sectional view, taken substantially on the line 7—7 of Fig. 3, looking in the direction of the arrows.

Ball-point pens of the character to which the present invention relates are usually provided with a two-part body or barrel, a portion of the front part or barrel section thereof being indicated at 1 in Fig. 4. This portion of the barrel is often composed of plastic material and sometimes of metal. The rear part of the barrel, sometimes referred to as the "cap" is indicated at 2. The two parts or barrel sections 1 and 2 are detachably coupled together by the screw threads 3, provided on a plug 4 that is force-fitted into the forward end of the rear barrel section or so-called "cap" 2. The front member 1 of the barrel is internally threaded at its rear end for reception on the threads 3. This is conventional pen construction forming no part of the present invention.

The ink cartridge is disclosed at 5, and the same is also

2

of conventional construction, consisting of a relatively slender tube containing an ink supply 6, and fitted in its forward end with the ball-point, not shown, but of known construction. The cartridge 5 is axially slideable within 5 the barrel sections 1 and 2, and also through the central aperture 7 in the plug 4, and it is normally urged toward the rear end of the pen by means of a coil spring surrounding its forward end, which spring is confined between a shoulder formed on the body of the cartridge and 10 a tapered portion inside of the barrel section 1. This arrangement is known and widely used in ball-point pen construction and hence is not illustrated herein.

A spring yoke is formed from the blank shown in Fig. 1. It will be therein noted that the blank consists of a 15 lengthy strip of springy metal provided at one end with a rounded projection 11. At its opposite end the strip is formed with a portion indicated at 12, of slightly less width than the width of the strip, and extending from this portion is a tongue 13 of less width than the width 20 of the part 12. Thus, shoulders 14 are provided on the end of the part 12 at the base of the tongue 13.

The blank shown in Fig. 1 is formed into the yoke member 10 by being transversely folded on the lines indicated at 15, 16, 17, 18, 19 and 20, resulting in the 25 yoke member shown in Figs. 2, 3, 4 and 6. Such yoke member is provided at its rear end with a loop portion 21 from the forward ends of which extend the lateral parts 22 forming shoulders for a purpose to be described. Extending divergently from the ends of the extensions 22 30 are the springy legs 23 and 24. The leg shown at 24 is that which is provided with the rounded protuberance 11. This protuberance 11 facilitates easy sliding movement of the yoke within the pen barrel. The part shown at 12 is formed on the free end of the leg 23, and said 35 part is bent on the line 25 to extend at right angles to the body of the leg 23, and the tongue shown at 13 is curled or bent over backwardly to form a rounded loop substantially as indicated at 26.

For the purpose of adding resilience and flexibility to 40 the spring legs 23 and 24 of the yoke, and to permit one size of yoke to be used in pens of various diameters, elongated slots 27 and 28 are provided in the body of the yoke adjacent to the base ends of the legs.

Fig. 4 shows how the yoke is fitted in position within 45 the rear barrel section or so-called "cap" 2 of the pen. It will be noted that this portion of the barrel of the pen is provided in its wall with an elongated slot 30 formed at its forward end with an enlarged portion 31. When the yoke 10 is fitted in place in the barrel section 50 2 the relatively narrow tongue portion 13, now bent into the loop 26, fits in and is slideable within the narrow portion of this slot. The portion 12 of leg 23 being wider than the narrow portion of slot 30, cannot enter into the slot until the yoke is moved forwardly to an 55 extent as to cause the part 12 to register with the wide portion 31 of the slot, whereupon the springiness of leg 23 will cause the part 12 to rise into the part 31 of the slot. This is shown in Fig. 4. It will be noted that when the parts are in this position, the cartridge 5 is in its projected or advanced position at which time its ball point is extended out of the forward end of the barrel section 1 and is in writing position, and will remain in such position as long as the wide portion 12 of the leg 23 is engaged with the wide portion 31 of the slot in the barrel section 2.

Secured to the barrel or cap section 2, is a pocket-engaging clip 39, provided at its forward end with the ball or enlargement 40 positioned over the wider portion 31 of slot 30. Thus, when the loop portion 26 is in the position shown in Fig. 4, at which time the yoke is in its advanced position, the loop 26 will be disposed under and in contact with the ball 40 of the clip. Finger

pressure imposed on the clip at the free end thereof, will cause the loop 26 to be depressed until the shoulders 14 are below the wall of the barrel section 2, or the portion 12 of leg 23 is forced out of the wider part 31 of the slot 30, whereupon the spring about the forward end of the cartridge will force the yoke 10 rearwardly, the loop portion 26 being guided in a narrow part of the slot during such movement.

The loop 26 is so formed that its end or terminal 32 constantly remains in the slot 30 whether the yoke 10 is advanced or retracted, so that the yoke therefore cannot be accidentally displaced by twisting movement, to disengage it from the slot.

The barrel section or cap 2 is provided at its rear end with the opening 33 through which the plunger or finger-piece 34 is axially guided. At its forward end, the plunger or finger-piece 34 is provided with a sleeve portion 35 into which the loop portion 21 of the yoke 10 is force-fitted, so that the yoke and the plunger are thus securely coupled together. The plunger may be made of metal or of plastic. A bead 35 is provided on the plunger to limit its rearward movement. The parts 22 of the yoke act as abutments, against which the rear end of the ink cartridge is held by its encircling spring.

From the foregoing, the structure and operation of the improved pen mechanism will be readily apparent. In the retracted position of the ink cartridge, the loop member 26 of the yoke 10 is located at the rear end of the narrow portion of slot 30 and the plunger is retracted to its maximum extent out of the back of the barrel section or cap 2. When the plunger is depressed to the position shown in Fig. 4, it will urge the yoke forwardly until the portion 12 thereon will register with the wider portion 31 of the slot 30, whereupon this portion 12 of the yoke will spring into that part of the slot and act to lock the yoke, and hence the ink cartridge, in its forward or writing position. When pressure is imposed on the clip 32, the loop 26 will be depressed to disengage the part 12 from the slot portion 31, whereupon the cartridge can be propelled rearwardly by its spring until the plunger reaches its limit of rearward movement as defined by the bead 35.

Having described a single embodiment of the invention, it is obvious that the same is not to be restricted thereto, but is broad enough to cover all structures coming within the scope of the annexed claims.

What I claim is:

1. A fountain pen construction comprising, a barrel, an ink cartridge mounted for limited axial movement therein, a spring surrounding the cartridge and acting to normally urge the same toward the rear of the barrel, the barrel having a slot in its wall, said slot having an elongated narrow portion and a shorter, wider portion at one end thereof, a springy, yoke-shaped member slidably mounted in the barrel, a plunger of hollow cylindrical form having a forward circular open end, the yoke-shaped member having a rectangular rear end inserted into the body of the plunger through the circular open end thereof, the yoke-shaped member having a pair of spring arms each of which is formed with a shoulder abutting against the end of the plunger to limit the insertion of said rectangular end of the yoke-shaped member into the plunger, one of said spring arms having an end formed into a loop extending into and slidably movable forwardly in the slot when the plunger is urged forwardly.

2. A fountain pen construction comprising a barrel, an ink cartridge mounted for limited axial movement therein, a spring surrounding the cartridge and acting to normally urge the same toward the rear of the barrel, the barrel being provided with a slot in its wall, said slot having an elongated narrow portion and a shorter wider portion at one end thereof, a yoke-shaped member of flat spring metal slidably mounted in the barrel and against which the rear end of the cartridge is urged by the spring, said yoke-shaped member having a pair of spring arms, one of which is formed with a shoulder near its free end and a reduced-width extremity extending beyond the shoulders, said extremity being formed into a backwardly-curved loop having an end portion located in the narrow portion of the slot, a hollow cylindrical plunger axially operative in the rear of the barrel and adapted, when manually depressed, to urge the yoke forwardly and cause it to propel the cartridge to advanced writing position, the wider portion of the yoke arm engaging in the wider portion of the slot when the yoke is so advanced to thereby retain the yoke in such advanced position, the narrower portion of the yoke arm having an extremity that always remains in the narrow portion of the slot to hold the yoke against rotative movement within the barrel, a clip on the barrel having an end behind which the loop on the yoke arm is positioned when the yoke is in its advanced position, the rear end of the yoke being rectangular and being fitted into the circular open end of the plunger with the major portion of each arm extending forwardly beyond the forward end of the plunger, and each of the arms of the yoke being provided with a shoulder to abut against the end of the plunger when the rectangular end of the yoke is fitted into the plunger.

3. In a fountain pen of the ball-point type, a barrel, a plunger operative through the rear end thereof, a yoke of flat spring metal slidable in the barrel and movable in one direction by the plunger, the plunger having a circular opening in its forward end, the yoke having a rectangular rear end inserted to a predetermined extent through said opening and into the interior of the plunger leaving the greater portion of each arm extending forwardly of the plunger, the yoke having divergent arms each of which is formed with a shoulder to limit the extent of insertion of the rectangular end of the yoke into the plunger by abutment of the shoulders against the end of the plunger, the yoke having one of its arms formed with a loop, the barrel having an elongated slot in which said loop travels, and the slot having a widened end portion into which the loop enters at the end of the forward travel of the yoke.

4. In a pen construction as provided for in claim 3, wherein the yoke is provided with elongated slots, which slots extend through the shoulders and partly into the portion of the yoke which enters the plunger, said slots also having parts located in a portion of each arm beyond the shoulders.
